UNITED STATES PATENT OFFICE

BERDIEN KLING, OF DUNN CENTER, NORTH DAKOTA

DOOR OPERATING MECHANISM

Application filed May 7, 1928. Serial No. 275,870.

This invention relates to operating mechanisms for horizontally swinging members, such as doors, gates and the like, the invention being especially adapted for use in connection with the doors of garages, so that the occupant of an automobile will not be required to get out for the purpose of opening or closing the doors.

To this end, the invention provides means operated by the weight of an automobile for opening the doors, said means including a depressible tread or treads, and novel and adjustable means actuated thereby and connected with the doors to operate the latter. The invention further includes means for holding the doors in open position and for releasing the holding means, the last mentioned means being both manually and automatically controlled.

With the above and other objects in view, the invention further includes the following novel features and details of construction, to be hereinafter more fully described, illustrated in the accompanying drawings and pointed out in the appended claims.

In the drawings:—

Figure 1 is an elevation showing the entrance to a garage with the invention applied.

Figure 2 is a section on the line 2—2 of Figure 1.

Figure 3 is a section on the line 3—3 of Figure 2.

Figure 4 is a bottom plan view showing the approach to the garage and illustrating the means for holding the doors in open position and the means for releasing the doors.

Figure 5 is an enlarged fragmentary sectional view showing the manner of pivotally mounting the doors.

Referring to the drawings in detail wherein like characters of reference denote corresponding parts, the reference character 10 indicates a portion of a garage whose entrance is adapted to be closed by a pair of doors 11. These doors are mounted for horizontal swinging movement and for this purpose the doors have extending from their top and bottom edges, pivots or trunnions 12, the latter operating in sockets 13 positioned at the top and bottom of the door frame. The pivots or

trunnions are spaced from the side edges of the doors, being located adjacent the side members of the door frame.

Hingedly mounted between spaced ears 14 positioned at opposite sides of an inclined approach 15 are the lower ends of arms 16. The upper ends of these arms are provided with spaced openings for the passage of a bolt 18 which is carried by a flexible joint 19 at one end of a rod 20. One of these rods is provided for each of the arms 16 and the inner ends of the rods have flexible connections 21 which carry bolts or fastening devices 22, by means of which the inner ends of the rods are secured to the doors beyond the trunnions 12.

The approach 15 is provided with an opening 23 and hingedly mounted within this opening as indicated at 24 is a tread 25. This tread may if desired be formed in two sections and is yieldingly forced upward by means of springs 26 positioned beneath the tread. Rigidly secured to opposite ends of the tread as shown at 27 are arms 28 whose outer ends operate in slots 29 provided in the lower ends of the arms 16.

The arms 28 thus have a sliding pivotal connection with the arms 16 so that when the tread 25 is depressed, the upper ends of the arms 16 will move inward toward the doors so as to open the latter as indicated by the dotted lines in Figure 2 of the drawings.

The above operation will occur when the front wheels of an automobile pass over the tread and when the latter is depressed, it will be held in depressed position by means of spring actuated latches 30 which are secured to the under face of the tread and which engage keepers 31 carried by the structure of the approach 15. The doors 11 will thus remain open so that the automobile may enter the garage. As soon as the latches 30 are released, the action of the springs 26 will force the tread upward so that the doors will be closed.

This release of the latches 30 may be effected by means of a cable 32 which operates over pulleys 33 carried by an arm 34. This cable passes through the approach structure and has connected thereto cables 35 which are

connected with the latches 30, so that a pull upon the cable 32 will retract the latches so as to release the tread.

In order that the doors may be automatically closed when the automobile leaves the garage, the cables 35 have connected thereto a cable 36 which extends through the approach structure and passes over a pulley 37 with its end anchored as at 38. As the automobile leaves the garage, it may be steered so that one of its front wheels will pass over the cable 36 and as this cable is raised above the plane of the approach, this portion of the cable will be depressed so as to pull upon the cables 35 and release the latches 30.

The invention is susceptible of various changes in its form, proportions and minor details of construction and the right is herein reserved to make such changes as properly fall within the scope of the appended claims.

Having described the invention what is claimed is:—

1. In combination with a building having an entrance and an inclined platform therefor and provided with an opening, a door for the entrance, trunnions carried by the upper and lower edges of the door and adjacent one of the side edges thereof, journals carried by the building to receive the trunnions, a treadle hinged at one end to the platform and closing the opening, operating means connected to the free end of the treadle and to the hinged edge of the door, tension means carried by the platform and engaged by the treadle to automatically return the treadle to its normal position when disengaged by a vehicle, a latch to hold the treadle in a door-opening position, and means to operate the latch to permit the tension means to close the door.

2. In combination with a building having an entrance and an inclined platform therefor and provided with an opening, a door for the entrance, trunnions carried by the upper and lower edges of the door and adjacent one of the side edges thereof, journals carried by the building to receive the trunnions, a treadle hinged at one end to the platform and closing the opening, a vertically disposed arm pivotally mounted at the lower end to the platform, an operating rod having universal connections between the door and arm, means connecting the free end of the treadle to said arm, tension means carried by the platform and engaged by the treadle to automatically return the treadle to its normal position when disengaged by a vehicle, a latch to hold the treadle in a door-opening position, and means to operate the latch to permit the tension means to close the door.

3. In combination with a building having an entrance and inclined platform therefor and provided with an opening, a door for the entrance, trunnions carried by the upper and lower edges of the door and adjacent one of

the side edges thereof, journals carried by the building to receive the trunnions, a treadle hinged at one end to the platform and closing the opening, a vertically disposed arm pivotally mounted at the lower end to the platform, an operating rod having universal connection between the door and arm, a second arm secured to the treadle and pivotally and slidably connected to the first mentioned arm, tension means carried by the platform to engage the treadle to automatically return the treadle to its normal position when disengaged by a vehicle, a latch to hold the treadle in a door-opening position, and means to operate the latch to permit the tension means to close the door.

In testimony whereof I affix my signature,
BERDIEN KLING.
